UNITED STATES PATENT OFFICE

2,502,924

FOLDING TOOTHBRUSH AND CONTAINER THEREFOR

Ted R. Stacey and Roy H. Lesner, Chicago, Ill., assignors, by mesne assignments, to Totebrush Inc., a corporation of Illinois

Application April 26, 1946, Serial No. 665,237

5. Claims. (Cl. 132—84)

1

This invention relates to toothbrushes, and particularly to a folding toothbrush combined with a receptacle to receive the toothbrush in folded condition, the assembly being small and compact and hence adapted for use by travelers and others to whom compactness and ease of portability are important considerations.

One principal object of the invention is to provide a folding toothbrush having a handle portion and a brush portion foldable with respect to one another, and novel means for locking the portions in extended position whereby a brush having substantially the same rigidity as a conventional toothbrush results, such means including members slidable with respect to the handle portion and engageable over two opposed faces of the brush portion.

Another object is to provide a folding tooth-brush having a handle portion and a brush portion hinged together and including a latch for locking the parts in extended, i.e., operative, position, the actuating part of the latch being so formed as to constitute a convenient and comfortable part of the handle.

Still another object is to provide a folding toothbrush as aforesaid and a case therefor, the latter having parts snugly fitting the folded brush to prevent foreign matter from contaminating the brush, the bristles whereof are concealed within the case.

Within the case.

A further object is to provide a folding tooth-brush and case as aforesaid, the case having a closed space therein to receive a powdered dentifrice or a container thereof, the space being accessible by means of a dust-proof closure.

Other objects will appear as the description proceeds.

"In the drawing illustrating one embodiment of our invention:

Fig. 1 is a perspective view of the case and the toothbrush in partially unfolded position, the brush being shown partly removed from the case; Fig. 2 is a cross-sectional view of the case showing the folded brush, in dotted lines, in its relation to the case.

Fig. 3 is a right-hand end elevational view of the case:

Fig. 4 is a cross-sectional view taken along the line 4-4 of Fig. 2:

Fig. 5 is a side elevational view of the brush latched in open position and ready for use:

Fig. 6 is a plan view of the brush as shown in Fig. 5:

Fig. 7 is a view similar to Fig. 5 but with a part thereof shown in cross section:

Fig. 8 is a cross-sectional view taken on the line 8-8 of Fig. 7.

Fig. 19 is a detail view of a part of the latch; and

Fig. 10 is a perspective view of an alternative form of case.

Turning to the drawing, the brush 10 includes two principal parts hereinafter for convenience referred to as the brush part 11 and the handle part 12. Part 11 includes a body portion 13 made of any suitable material, e.g., plastic composition, and has embedded therein the plurality of tufts of bristles 14, the transverse cross-sectional contour of the body being preferably substantially rectangular as shown. The handle part 12, including a body portion 15, is of similar material and transverse cross section, and each of the parts 13 and 15 is provided at their juxtaposed ends with ears 16-16 and 17-17 through apertures in which pass the pivots 18-18 to form a hinged connection, whereabout the parts 11 and 12 may be folded into the compact form indicated in dotted lines in Fig. 2.

25 To maintain operative alignment of parts 11 and 12, there is provided latch means including a pad 21, a finger 22, and a screw 23, all slidable as a unit with respect to body portion 15. Finger 22 is preferably of stainless steel for strength and resistance to rusting, and is slidable in aligned recesses 24 and 25 in the portions 15 and 13, respectively. Screw 23 is preferably of stainless steel, is shouldered to abut the finger 22 (Fig. 27), and is threaded thereinto, the head of the screw lying in a counterbored part 26 of aperture 27, passing through the pad 21. Thus finger 22 is slidable longitudinally of the brush upon corresponding sliding movement of pad 21. It is to

be noted that by sinking the finger 22 within the recess 24, a flush surface is provided on the rear face of the unfolded brush, and with this the absence of objectionable projections, which would prove uncomfortable to the user. Moreover it is to be noted that the latch operating pad is curvilinear on its exterior face to fit comfortably within the fingers of the user. To afford

ford clearance for the shank of the screw 23, the portion 15 is longitudinally slotted at 31, and to guide the pad 21 the portion 15 (Fig. 18) and pad 21 are provided respectively with interlocking tongues 32-32 and grooves 33-33. It will be comprehended that pivots 18-18 may be of any suitable length or even comprise a single pivot extending from one side of the brush to the other. In such case the latch member 22 in its movement to locking position would take up

a position intermediate the pivot and the bottom of the recess 24 thereby to supplement the locking action by restraining tendency of the latch to bend upon application of excessive force by the user.

Accordingly, when pad 21 is to the right, as seen in Fig. 7, the pad and finger 22 lie against opposite faces of the brush portion 13 to retain the same in extended position with respect to the handle portion 12; and when pad 21 is moved to the left, the pad and finger are freed from engagement with portion 13 to permit the latter to be folded about handle portion 15 and into the position of Fig. 2. If desired, the outer convex face of pad 21 may be corrugated or knurled for more positive engagement by the fingers.

One of the outstanding advantages of the instant construction resides in utilizing both the latch and the latch operating pad to render the unfolded brush rigid while in use. Thus, referring to Fig. 7 it is noted that the finger 22 and pad 21, when in locking position, embrace between them the brush portion 13, and by careful fitting of the parts, i. e., providing minimum sliding clearance, the brush portion 13 may be made quite rigid with respect to the handle portion 15.

The case (Figs. 2 and 4) for receiving the folded brush and the dentifrice comprises a box-like housing, preferably of molded plastic composition, having side walls 41, a bottom wall 42, a top wall 43, a front wall 44, and a rear wall 45. Side walls 41 and front wall 44 extend upwardly beyond wall 43 to provide with the same a compartment into which the folded brush may be snugly fitted (Figs. 2 and 3). By allowing the hinged connection to protrude beyond the wall 45, manual engagement of the brush for removal thereof from the case is facilitated. In order to receive the bristles 14 of the brush, wall 43 is offset for a portion of its length (Fig. 2) and wall 44 is extended upwardly to meet handle portion 15 whereby the bristles are confined in a space which is closed except for the ventilating perforations 46 in walls 41 whereby consequent drying of the damp bristles may be accelerated.

To secure the brush more firmly intermediate the walls 41, the latter may be provided with shallow depressions 47 with which corresponding protrusions 48 (Fig. 6) on the handle portion 15 may engage, the inherent elasticity of the walls 41 permitting such engagement and subsequent easy disengagement.

It is to be noted particularly from Fig. 2 that when the brush is in assembled position, the ears 16-16 and 17-17 protrude beyond the side walls 41-41 thereby providing a handle or finger-piece for dislodgment of the brush from its compartment when it is to be removed for use.

Walls 41, 42, 44, and 45 together define a compartment 51 for the reception of powdered or liquid dentifrice, access to such compartment being by way of a knurled screw plug 52 threadedly inserted in an aperture 53 in wall 44.

As an alternative form of case, the embodiment of Fig. 10 may be provided. In so far as the relationship of the folded brush and case are concerned, the description hereinbefore is deemed sufficient. However, for use by those who prefer paste dentifrice in a tube, the front wall 44 is modified as shown. Thus the walls 41 are grooved at 61-61 to receive the corresponding tongues 62 of the sliding closure 63, the latter forming with the walls 41, 42, 43, and 45 a compartment 64 for the reception of a tube of denti-

frice 65. A recess 66 in the outer face of the closure 63 permits engagement by a finger to slide the closure from closed to open position for removal and insertion of the tube 65 in the compartment 64. When closure 63 is moved to closing position, an integral projection 67 therein will abut wall 43 to limit movement thereof, and when closure 63 is moved to open position, the inwardly curved extremity 68 will abut the wall 43 to limit movement in that direction. It will be understood that projection 67 will be assembled with closure 63 after the latter has been engaged with the grooves 61.

While we have shown particular embodiments of our invention, it will be understood, of course, that we do not wish to be limited thereto since many modifications may be made, and we therefore contemplate by the appended claims to cover any such modifications as fall within the true spirit and scope of our invention.

Having thus described our invention, what we claim and desire to secure by Letters Patent is:

1. A folding toothbrush or the like and a receptacle therefor, the receptacle comprising a body having a dentifrice-holding chamber and a brush-receiving compartment, the body having side walls, end walls and top and bottom walls, the side walls being extended beyond said top wall to define said compartment, the toothbrush including a brush part and a handle part and hinge means interconnecting said parts to enable said brush to be folded for insertion in said compartment, the said side walls having projections extending interiorly thereof, and at least one of said brush parts having depressions adapted to be engaged by said projections, the said extended portions of said side walls being comprised of resilient material to facilitate engagement of said projections with said depressions.

2. A folding toothbrush or the like and a receptacle therefor, the receptacle comprising a body having a pair of side walls, a pair of end walls, a bottom wall and a partition wall spaced below the top of the side walls to define with the side walls, end walls and bottom wall a dentifrice-receiving chamber, said chamber having an aperture and a closure therefor for access to the interior thereof, the extension of said side walls beyond said partition wall forming a brush-receiving compartment, said brush including a brush part and a handle part and hinge means interconnecting said parts to enable said brush to be folded for insertion in said compartment, the width of said brush being equal to the distance between said extended side walls, and said side walls being comprised of resilient material whereby upon assembly of the folded brush intermediate said side walls frictional engagement of the brush results.

3. A folding toothbrush or the like and a receptacle therefor, the receptacle comprising a body having a pair of side walls, a pair of end walls, a bottom wall, and a partition wall spaced below the top of said side walls to define a dentifrice-receiving chamber, the extension of said side walls beyond said partition wall forming a brush-receiving compartment, said brush including a brush part and a handle part and hinge means interconnecting said parts to enable said brush to be folded for insertion in said compartment, the folded length of said brush being equal to the length of said side walls, and the hinge means, when the folded brush is assembled in said receptacle, protruding exteriorly of said side

walls to provide a finger piece for removal of said brush from said receptacle, and frictional means common to said brush and side walls for maintaining the folded brush in assembled position in the compartment.

4. A folding toothbrush or the like and a receptacle therefor, the receptacle comprising a body having a dentifrice-holding chamber and a brush-receiving compartment, the body having side walls, end walls and top and bottom walls, the side walls being extended beyond said top wall to define said compartment, the toothbrush including a brush part and a handle part and hinge means interconnecting said parts to enable said brush to be folded for insertion in said compartment, the said side walls having projections extending interiorly thereof, at least one of said brush parts having depressions adapted to be engaged by said projections, the said extended portions of said side walls being comprised of resilient material to facilitate engagement of said projections with said depressions, the outer surface of the folded brush and the outer edges of the walls being so constructed and arranged as to be coterminous and to form one substantially unbroken surface when the brush is inserted into the compartment.

5. A folding toothbrush or the like and a receptacle therefor, the receptacle comprising a body having a pair of side walls, a pair of end walls, a bottom wall and a partition wall spaced below the top of the side walls to define with the side walls, end walls and bottom wall a dentifrice-receiving chamber, said chamber having an aperture and a closure therefor for access to the

5
